STABILIZING PROP FOR AN ELONGATED TANK-TYPE SUCTION CLEANER

Raymond Descarries, Montreal, Quebec, Canada, assignor
to Aktiebolaget Electrolux, Stockholm, Sweden, a cor-
poration of Sweden

Application April 1, 1958, Serial No. 50,283

Term of patent 14 years

(Cl. D9—2)

FIG. 1

FIG. 2

FIG. 3

FIG. 4

FIG. 5

FIG. 6

FIG. 7

Fig. 1 is a rear elevational view of a stabilizing prop for an elongated tank-type suction cleaner, showing my new design;

Fig. 2 is a front elevational view thereof;

Figs. 3 and 4 are respectively top and bottom plan views thereof;

Fig. 5 is a side elevational view thereof;

Fig. 6 is an enlarged perspective view thereof; and

Fig. 7 is an enlarged bottom perspective view thereof.

1 claim:

The ornamental design for a stabilizing prop for an elongated tank-type suction cleaner, as shown.
